UNITED STATES PATENT

CHARLES D. OLSEN, OF DENVER, COLORADO.

CARBURETER.

1,171,235.

Specification of Letters Patent.

Pa

Application filed January 25, 1915. Serial No. 4,143.

To all whom it may concern:

Be it known that I, CHARLES D. OLSEN, a citizen of the United States, residing in the city and county of Denver and State of Colorado, have invented certain new and useful Improvements in Carbureters; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in carbureters, my object being to provide a device of this character which shall be an improvement over the constructions now in use, at least so far as I am aware.

20 An important feature of my improvement consists in locating the throttle or main valve for controlling the entrance of air, between the air inlet and the needle valve which controls the entrance of the combustible element, as gasoline. By virtue of this arrangement, the needle valve mechanism is located entirely within the vacuum chamber or the chamber where the partial vacuum condition exists, which is advantageous particularly when the engine is running at low speed and when the throttle valve is nearly closed.

In order to overcome the difficulty incident to the use of the constructions of carbureters heretofore employed, an auxiliary automatic valve has been located at the air inlet of the conduit, the throttle valve being on the engine side of the needle valve, as heretofore explained. This arrangement requires a complicated and expensive device, which, at the same time, is cumbersome and unsatisfactory. By virtue of my improvement, however, the construction is extremely simple and economical and at the same time, gives increased efficiency as compared with any construction heretofore employed, so far as I am aware. In addition to the general feature of locating the throttle valve on the air inlet side of the needle valve, I provide special means for simultaneously adjusting the throttle valve and the needle valve.

the throttle valve and the needle valve, the tremity of the chamber

extends downwardly beyond the chamber 21 and its lower extremity is provided with a disk or plate 29 which rests upon the periphery of an eccentric cam 30 mounted on a 5 spindle 31 which is journaled in the wall 17, as shown at 32 and 33. One extremity of the spindle extends beyond its bearing on one side, as shown at 34 and to this protruding extremity is secured, as shown at 35, one extremity of an arm 36, whose opposite extremity is equipped with a regulating screw 37, which is threaded into said arm, as 10 shown at 38, the upper extremity of the screw bearing against an eccentric cam 39 which is fast on a spindle 40 journaled in the wall 41 of the air inlet passage 42. Mounted on the spindle 40 and located within the passage 42, is a throttle valve 43. The upper extremity of the adjusting screw 37 15 is held in contact with the periphery of the cam 39 by means of a spring 44 which is secured to the wall 41 and extends underneath the arm 36, the said spring being under sufficient tension to perform the aforesaid function as the cam 39 is rotated through the medium of a crank arm 45 whose extremity opposite the spindle 40 is pivotally connected, as shown at 46, with a manually operated rod 47 whose extremity opposite the crank 45 is accessible to the chauffeur or person in charge of the machine, or the engine with which the carbureter is employed.

Between the enlarged threaded part 27 of 20 the tube 25 within the chamber 21 of the carbureter and the disk 29, is located a spring 48 which surrounds the protruding extremity of the needle valve and acts on the disk 29 to maintain the latter at all times in contact with the periphery of the cam 30.

From the foregoing description, it will be understood that if we assume that the throttle valve 43 and the needle valve 24 are both closed, the parts in this event being in the 25 position illustrated in Figs. 3 and 4, whereby the disk 29 and the upper extremity of the set screw 37 are respectively in engagement with the eccentric cams 30 and 39 at their points of maximum eccentricity, if it 30 is desired to open the throttle valve and the needle valve, the operator will pull upon the rod 47, whereby the crank arm 45, the spindle 40 and the cam 39 will be actuated to open the throttle valve, a corresponding movement will be imparted to the needle valve, since as the eccentric cam 39 is actuated, the engaging extremity of the screw 37 will, by virtue of its being held in contact with the periphery of said cam, approach the center of the spindle 40, which movement of the said screw and the arm 36 carried thereby will impart a corresponding movement to the eccentric cam 30, through the medium of the spindle 35. Hence, as the

disk 29 of the needle valve is pressed against 65 the periphery of the eccentric cam by the spring 48, the needle valve will move downwardly or approach the center of movement of said cam, whereby the conical end 23 of this valve will move out of the opening 22 70 of the chamber 21, allowing the gasoline or other volatile liquid to enter the chamber 21 and pass thence to the manifold of the engine simultaneously with the entrance of the air through the passage 42, as the throttle valve is opened, the two valves being correspondingly opened in order to obtain a proper combustible mixture of air and volatile liquid.

In order that the position of the carbureter may be changed with reference to the receptacle 6, the chamber 21 is provided with a web 50 extending at right angles to the web 20 and having a passageway 51 communicating with the space 26 of the chamber 21. When the passage 19 is employed to admit the gasoline or other volatile liquid to the chamber 21, the passage 51 is closed by a stop plug 52. However, should it for any reason be desirable to 90 change the position of the carbureter with reference to the receptacle 6, the chamber 21 may be disconnected from the receptacle by unscrewing the chamber from the nipple 15, inserting the plug 52 in the recess formerly 95 occupied by the threaded part of the nipple, and connecting the chamber 17 with the nipple, whereby the passage 14 of the latter shall register with the passage 51 of the web 50.

In order that the height of the fluid within the receptacle 6 may be seen at all times, a gage 53 is employed, the same being equipped with a transparent plate 54 through which the level of the liquid within 105 the receptacle may be observed.

Having thus described my invention, what I claim is,—

A carbureter having a throttle valve and a needle valve, the needle valve being located between the throttle valve and the engine, the needle valve comprising a stem and a casing in which the stem is located, the said casing having an opening normally closed by the valve piece of the stem, the 110 said stem projecting beyond the casing and having a stop at its exposed extremity, a spring surrounding the stem between the needle-valve casing and said stop, a rock spindle located below the stem of the needle 115 valve and carrying an eccentric cam, against which the exposed extremity of the needle valve is pressed by the said spring, an arm secured to the rock spindle and carrying a screw threaded into one extremity thereof, 120 the stem of the throttle valve carrying an eccentric cam whose periphery is engaged by the said screw, means acting on the said

arm for pressing the screw against said cam, a crank arm secured to the stem of the throttle valve, and an operating rod connected with said crank arm, whereby as the throttle valve is actuated, a corresponding predetermined movement is imparted to the needle valve.

In testimony whereof I affix my signature in presence of two witnesses.

CHARLES D. OLSEN.
